UNITED STATES PATENT OFFICE.

THEODORE D. ROBINSON, OF ALBANY, NEW YORK.

VENTILATING SUBWAYS.

No. 849,814.

Specification of Letters Patent.

Patented April 9, 1907.

Application filed May 1, 1906. Serial No. 314,679.

To all whom it may concern:

Be it known that I, THEODORE D. ROBINSON, a citizen of the United States, residing at Albany, in the county of Albany and State 5 of New York, have invented a new and useful Improvement in Ventilating Subways, of which the following is a specification, reference being had to the accompanying drawings, forming part thereof.

10 The object of my invention is to provide a new and improved means for disposing of the vitiated atmosphere and gases in a subway, that is entirely hidden from sight and discharges its vitiated contents at the highest 15 point possible without erecting unsightly means for so discharging it.

Figure 1 shows a longitudinal sectional view of the ordinary entrance-way from the street to a subway, showing the kiosk and 20 housing of the entrance excavation and my means or invention shown in a similar sectional view. Fig. 2 shows a longitudinal sectional view of one of my revoluble transparent shutters; Fig. 3, a vertical sectional view 25 of one end of the housing, taken on line *a a* of Fig. 1; Fig. 4, a vertical sectional view of a subway and kiosk, with my invention shown partly in side elevation and partly in vertical section; and Fig. 5, a vertical sectional view 30 of another form of my invention.

The numeral 1 shows the kiosk, and 2 the housing over the entrance, the roof of the housing and sides of the kiosk being of transparent material, as glass, so that the 35 entrance may be more or less lighted by the daylight.

At 7 is seen a ceiling which in part covers the entrance-space, but leaves a considerable space between it and one side of the kiosk, 40 leaving an entrance to the open-sided chamber 10. From this opening and in operative connection therewith drops the conduit 6 and passes longitudinally underneath the roof of the housing and drops again at the rear 45 end of the housing and passes into the subway forming the passage-way 3', thus forming a conduit which receives the foul air and gases in the subway directly under its crown or arch and by natural draft carries them 50 away, emptying them in the open chamber 10, whence they escape to the atmosphere. This conduit 6 is preferably made of transparent material and has pivoted portions, as seen at 6' in Figs. 1 and 2, which swing so 55 they may be opened and closed at pleasure, so they may readily be cleaned and then shut

again, forming a closed conduit in that portion at least which receives the light of the sun, and thus its light is made use of in lighting the entrance-way, kiosk, and housing. 60 That portion of the conduit that lies under the arched roof of the subway has a damper 6' to shut off the action of the draft whenever desired and also has a trap-door dropping downward, as seen at 6'', the object being 65 that if a train is passing in the direction of the arrow *b* the hanging door 6'' will direct the forward-moving air into the conduit 6 with more or less force and assist the natural draft already in the conduit, the damper 6' 70 being open. 3 denotes the rear transparent end of the kiosk, 4 the sidewalk, and 9 the earth or ground, and 8 the stairs to the entrance-way. In Fig. 4 is shown how the conduit is brought into the subway and 75 showing it as running along the top of the wall and lower edge or the arched roof of the subway, and I also show at 6' a branch conduit laid along the arch or the roof of the subway and in operative connection with the 80 conduit 6, discharging its contents into that conduit. There may be as many branch conduits as desired, those over or near to the trains passing over track B and going in a direction to force any pressure the motion 85 of the train may make into mouth *b'* and those trains moving on track A forcing it into mouths turned in the opposite direction to mouth *b*.

The above construction described so far is 90 intended for subways already constructed; but where a new subway is in process of construction then my preferred way of ventilating it is seen at 6' in Fig. 4, which consists of simple conduits rising from the very apex of 95 the roof of the subway preferably, passing preferably under ground to a kiosk and in operative connection with the conduit 6. This construction relieves the subway from containing any part of the conduit. The conduit is hidden from view and can be run any reasonable distance to a kiosk or to any other structure answering the purpose, and in this manner a subway may be fully ventilated. 100

In Fig. 5 I show that the conduit 6 may be in form of an arch corresponding with the arch of the roof of the subway and may have openable doors 7', the upright part of the conduit 6 being a part and portion of a kiosk 110 or other appropriate structure, the kiosk not being shown for want of room. The inven-

tion as shown in Fig. 4 may be used entire, if desired, or the conduits shown inside the subway may be omitted, if desired. The conduit 6 may take up the whole of the side 5 of a kiosk or only a portion, if desired. By my arrangement of my ventilating apparatus nothing unsightly is presented in the street, such as open holes, chimneys, or other structures that would not only be unsightly, but 10 obstructions to the streets. By use of that form of my invention shown at 6⁵ in Fig. 4 a number of the conduits 6⁵ can be run to the same kiosk and discharge through conduit 6 without disturbing patrons by foul smells and 15 bad air, as is now done in the present way of attempting to ventilate the subways by having the foul air escape bodily up the stairway among the patrons and entirely fill the housing.

20 Having fully described my invention, so that others may know how to make and use the same, what I desire to secure by Letters Patent is—

1. The combination with a subway and an 25 entrance thereto having the usual flight of steps, of a transparent housing or kiosk for said entrance comprising an elevated portion over the upper portion of said flight of steps and a dropped portion over the lower portion

of the flight, and a transparent conduit leading from adjacent the roof of said subway upward along the end of said dropped portion, thence horizontally beneath the roof thereof, and thence upward to and through the roof of the elevated portion. 30

2. The combination with a subway and an entrance thereto having the usual flight of steps, of a transparent housing or kiosk for said entrance comprising an elevated portion over the upper part of said flight of steps and a dropped portion over the lower part of the flight, and a transparent conduit leading from adjacent the roof of said subway upward along the end of said dropped portion, thence horizontally beneath the roof thereof, 40 and thence upward to and through the roof of the elevated portion, said conduit having its inner wall formed of a series of sections hinged to swing transversely of the conduit to facilitate cleaning. 45

50 In testimony whereof I have signed my name to this specification in the presence of two subscribing witnesses.

THEODORE D. ROBINSON.
